AUTOMOBILE WINDOW CRANK

Alex Kraus, Los Angeles, Calif.
(1650 W. Rosecrans Ave., Gardena, Calif. 90249)

Filed Apr. 7, 1969, Ser. No. 16,598

Term of patent 14 years

Int. Cl. D8—03

U.S. Cl. D8—161

FIGURE 1 is a front view of the automobile window crank;

FIGURE 2 is a side elevation view of the automobile window crank;

FIGURE 3 is a rear view of the automobile window crank; and

FIGURE 4 is an end view of the automobile window crank rotated 90° from the side elevational view of FIG. 2.

I claim:

The ornamental design for an automobile window crank, as shown.
